PENCIL

Kay Miller, New Brunswick, N. J., assignor to
Joseph Dixon Crucible Company, Jersey City,
N. J., a corporation of New Jersey

Application May 18, 1939, Serial No. 274,358

5 Claims. (Cl. 120—21)

The invention relates to an improvement in pencils, and more particularly to an improvement in refillable, mechanical pencils especially adapted for use by draftsmen, artists and the like. In 5 the use of mechanical pencils of this character, when the "lead" or other marking material has become worn or broken it is necessary to loosen the lead-holding devices and manually advance or pull out the lead a predetermined distance and 10 then close down the lead-holding devices on the lead, as distinguished from the operation of refillable mechanical pencils especially designed for use by the general public in which, when it is desired to have a fresh supply of lead, it is only 15 necessary to turn the body portion of the pencil or parts connected therewith in either clockwise or counter-clockwise direction to present a fresh length of lead for use.

There are on the market various forms of refillable, mechanical pencils designed especially for the use of draftsmen and artists as distinguished from refillable mechanical pencils designed for use by the general public. A basic requirement of the mechanical pencils for use by draftsmen and 25 artists is that the lead or other marking material be held firmly in place so that regardless of the pressure exerted upon the lead, it will not recede into the hollow body portion of the pencil. In this type of pencil the "lead" or other marking 30 material, which may be composed of graphite or a composition of colored ingredients, is held by contractile jaws. The central, longitudinal bore extending through the jaws and the body portion of the pencil is usually of a predetermined 35 diameter and accommodates a stick or sticks of marking material of substantially one size. These contractile jaws as heretofore constructed have in the majority of commercial forms of refillable, mechanical pencils adapted for drafting and artistic work, been connected at their inner 40 end with the outer end of a hollow member integrally connected with an element detachably secured to the body portion of the pencil or with an intermediary element mechanically connected 45 therewith. To bring the jaws against the stick or shaft of marking material, a cap member is provided having an internally threaded inner end and an internally tapered outer end which is adapted to engage with the outer end, usually 50 tapered, of the lead-holding member. The difficulty with this form of construction is that by reason of its fixed connection at its inner end with the body portion of the pencil, it has a relatively short period of effective gripping of the marking 55 material. Moreover, if by chance the shaft or

stick of marking material should be pushed into the outer end of the chuck or lead-holding member, it is a matter of considerable difficulty to project the lead from the chuck, and various expedients have been used to accomplish this act, 5 as by providing the opposite end of the pencil with a removable cap, so that an instrument may be inserted therein to push the lead forward and extrude it from the chuck.

One object of the present invention is to produce a refillable, mechanical pencil especially adapted for use by draftsmen and artists which will hold the leads or sticks of marking material more firmly than they are held in this type of refillable mechanical pencils on the market today 15 and which are so constructed and arranged that when the lead is broken or worn down flush with the outer end of the pencil the removal of the cap gives access to a longitudinally-movable lead-holding member so that an appropriate amount of 20 lead may be drawn outwardly and then the lead-holding member slid back to normal position after which the cap may be placed thereon to hold it firmly. Another object of the invention is to produce a lead-holding means for refillable 25 mechanical pencils which will be more durable in use than the lead-holding means with which refillable mechanical pencils are at present provided. To these ends the invention consists in the improved refillable mechanical pencil hereinafter fully described and particularly pointed 30 out in the appended claims.

In the accompanying drawing illustrating the preferred form of the invention, Fig. 1 is a side elevation of the lead-holding end of the improved 35 pencil; Fig. 2 is a longitudinal section, in enlarged view, through the pencil parts shown in Fig. 1 and indicating the position of the parts prior to bringing the lead-holding member into gripping engagement with the lead; Fig. 3 is a 40 view similar to Fig. 2, but showing the position of the parts when the lead-holding member has been brought into gripping engagement with the lead; Fig. 4 is a transverse section taken on the line 4—4 of Fig. 3; and Fig. 5 is a longitudinal 45 section of the lead-holding member.

The body 8 of the improved refillable mechanical pencil is an elongated member and may be composed of wood, metal or other suitable material and be either cylindrical or polygonal, and 50 provided at one or both ends with means for holding a "lead" or other marking material composed of graphite or colored composition. To accommodate the lead 9 the pencil body 8 is provided with a longitudinal bore 10. These parts may be 55

of the usual construction and arrangement found in refillable mechanical pencils.

The improved devices of the present invention for removably holding the lead in fixed position in one or both ends of the pencil body comprises a sleeve 12 having a longitudinal bore 13 and threaded externally to screw into the enlarged outer end of the bore 10 of the pencil body 8 and having a projecting externally threaded outer end 14. A nut 15 which may be either cylindrical or polygonal, in the present instance, polygonal, to conform with the periphery of the pencil body 8, is threaded onto the sleeve 12 to lock the sleeve 12 in the outer end of the pencil body by a tight engagement with the outer end of the pencil body. For this purpose the inner end of the nut 15 is provided with a tapered countersunk recess 17 which fits snugly over the corresponding tapered outer end 18 of the pencil body. It will be understood that when the internal taper 17 of the nut 15 fits over the external taper 18 and the nut is turned inwardly so as to bring the corresponding tapers into tight engagement, the sleeve 12 is firmly locked in the outer end of the pencil body, with the externally threaded end 14 of the sleeve 12 projecting outwardly therefrom.

The pencil-holding member is collet-like in form and consists of a cylindrical element 20 provided with a longitudinal bore 21 which may be of any preferred diameter to accommodate sticks of graphite or other black or colored marking material of various diameters. The inner end 22 of the lead-holding member has a smooth cylindrical periphery which is adapted to have a sliding fit in the outer cylindrical bore 24 of the sleeve 12 so as to be readily removable therefrom. The outer end of the lead-holding member is slotted longitudinally, at a plurality of points, in the present example three, as indicated by the reference numeral 25, so that the outer end of the member 20 will be collapsible upon the lead inserted therein.

The means for collapsing the outer end of the member 20 to bring it into gripping engagement with a lead is a cap 26 the inner knurled end 27 of which is internally threaded to screw over the external thread of the outer end of the sleeve 12. The outer end of the cap 26 is provided with an internal taper 28 which is adapted to close down upon the external taper 29 formed on the periphery of the outer enlarged end 30 of the lead-holding member 21.

Assuming that the operating parts of the lead-holding elements of the improved pencil are in the condition shown in Fig. 2 and that a lead of substantially the same diameter as the internal diameter 21 of the lead-holding member 20 has been slid longitudinally into the pencil, the cap 26 is turned inwardly until the internal taper 28 of the cap 26 fits snugly against the externally tapered outer end 29 of the member 20, which is known by the fact that it is impossible to turn the cap 26 further, the collapsible outer end of the member 20, made so by the longitudinal slots 25, is brought into firm gripping engagement with the lead, a grip so firm that it is impossible in any ordinary use of the pencil to push the lead inwardly into the body of the pencil. When it is desired to extend the protruding end of the lead it is simply necessary to unscrew the cap 26 slightly and pull outwardly on the lead the desired dis-

tance and then again screw inwardly on the cap 26. If by chance the lead should become broken flush with the outer end of the cap 26, the lead may be readily pulled out by completely unscrewing and removing the cap 26 and then by the fingers collapsing the outer end of the member 20 onto the lead and pulling outwardly thereon, so as to remove it from the sleeve 12. The member 20 is then moved inwardly relatively to the lead and again inserted into the sleeve 12, after which the cap 26 is screwed inwardly onto the outer end of the sleeve. In like manner when the lead has been used down to the minimum of usable length, the stub may be easily pushed out of the lead-holding member 20 and a fresh length of lead inserted therein.

From the foregoing description it will be understood that the improved refillable mechanical pencil of the present invention provides a simple, strong and durable means for so firmly gripping the lead that it cannot move or be pushed inwardly into the pencil body by pressure exerted upon it during use, and that if the projecting end of the lead should become broken flush with the end of the holding means, a fresh length of lead may be pulled outwardly from the pencil body by first unscrewing the cap, then pulling out the lead-holding member from the sleeve, then holding the lead and reinserting the lead-holding member into the sleeve, after which the cap may be screwed inwardly into place.

Having thus described the invention, what I claim as new is:

1. A pencil of the character described comprising an elongated body having a longitudinal bore in one end, a sleeve threaded into the bored end of the pencil body and having an externally threaded outer end, a lead-holding member the inner end of which is slidably received in the outer end of the sleeve, the outer end of the lead-holding member being composed of collapsible jaws and having a tapered periphery, and a cap having an opening at its outer end and having an internally tapered outer end adapted to fit over the tapered portion of the lead-holding member and an internally-threaded inner end adapted to be screwed onto the outer end of the sleeve, the opening in the outer end of the cap being of a diameter slightly greater than the diameter of the outer end of the lead holding member for spacing the outer end of the cap from the lead.

2. A pencil of the character described comprising a body having a longitudinal bore therein, a sleeve fixed in one end of the pencil body and having a projecting outer end, a lead-holding member slidably received in the projecting end of the sleeve and having a collapsible outer end, and a cap having an opening at its outer end for collapsing the outer end of the lead-holding member onto a lead, the opening in the outer end of the cap being of a diameter slightly greater than the diameter of the outer end of the lead holding member for spacing the outer end of the cap from the lead.

3. A pencil of the character described comprising an elongated body having a longitudinal bore therein, a sleeve secured in one end of the bore and having a projecting, externally threaded outer end, a lead-holding member the inner end of which is slidably received in the outer end of the sleeve and the outer end of which is longitudinally slotted so as to be collapsible upon a lead, and a cap having an opening at its outer

end mounted on the outer end of the sleeve for collapsing the outer end of the lead-holding member to bring it into gripping engagement with the lead, the opening in the outer end of the cap being of a diameter slightly greater than the diameter of the outer end of the lead holding member for spacing the outer end of the cap from the lead.

4. A refillable pencil comprising a body having a longitudinal bore for accommodating a lead, an externally-threaded sleeve threaded into one end of the body, a nut carried by the sleeve for locking the sleeve in the body, a lead gripping device having a central longitudinal bore for receiving the lead, the periphery of the inner end of the lead gripping device being arranged to have a snug sliding fit in the outer end of the sleeve, the outer end of the lead gripping device being slotted and the periphery thereof being tapered, and a cap having an opening at its outer end and tapered internally at its outer end to fit over the tapered outer end of the lead gripping device and having an internal thread at its inner end to screw onto the outer end of the sleeve so as to collapse the outer end of the lead gripping device to close it upon the lead, the opening in

the outer end of the cap being of a diameter slightly greater than the diameter of the outer end of the lead holding member for spacing the outer end of the cap from the lead.

5. A pencil of the character described comprising an elongated body having a longitudinal bore therein, a sleeve secured in one end of the bore and having a threaded portion projecting therefrom, a lead-holding member having a central bore for receiving a lead slidably mounted in the outer end of the sleeve, the outer end of the member being slotted longitudinally and having a tapered periphery, and a cap having an opening at its outer end and the inner end of which is threaded internally for engagement with the outer end of the threaded portion of the sleeve and the inner surface of the outer end of which is tapered to fit over the tapered end of the lead-holding member to collapse it into gripping engagement with the lead, the opening in the outer end of the cap being of a diameter slightly greater than the diameter of the outer end of the lead holding member for spacing the outer end of the cap from the lead.
